UNITED STATES PATENT OFFICE.

SAMUEL J. LAVEZZI, OF CHICAGO, ILLINOIS.

CORNER-BLOCK FOR BEDSTEADS.

1,375,850.

Specification of Letters Patent. Patented Apr. 26, 1921.

Application filed September 15, 1919. Serial No. 323,785.

To all whom it may concern:

Be it known that I, SAMUEL J. LAVEZZI, a citizen of the United States, residing at Chicago, in the county of Cook and State of Illinois, have invented certain new and useful Improvements in Corner-Blocks for Bedsteads, of which the following is a specification.

The object of my invention is to provide 10 a simple and efficient construction of corner blocks made of sheet metal and adapted to take the place of the ordinary corner blocks made of castings. Such castings are open to many objections chief among which may be 15 mentioned, first, the fact that inasmuch as they are rough castings and are not machined they do not fit properly with the end of the side rails and end rails with the result that such heads are frequently broken 20 and repairs are expensive and sometimes impossible; and second, the fact that there is no standard as to these corner blocks made of castings, that is standard either in size or character and consequently when a manufacturer goes out of business or discontinues 25 any line of construction the repair parts are unobtainable and repairs are impossible.

My construction of corner block overcomes the several objections to the old form 30 of blocks particularly because the same are indestructible and adapted to coöperate with the side rails and end rails in a manner so that they may be readily attached to and detached from the corner block.

35 In the drawings Figure 1 is a plan view of one of the sheet metal pieces of which my corner block is composed, the same being shown in its flat form before bending to shape; Fig. 2 a corresponding view of the 40 other piece composing my corner block; Fig. 3 a plan view of one of my corner blocks with adjacent ends of the side rail and end rail showing one of the bed posts, such post being either the upper left end one or the 45 lower right end one; Fig. 4 a sectional elevation on the line 4—4 of Fig. 3; Fig. 5 a section on the line 5—5 of Fig. 3; Fig. 6 a sectional elevation of the corner block and post viewed from the outer side of the bed; Fig. 7 50 a section on the line 7—7 of Fig. 8; Fig. 8 a section on the line 8—8 of Fig. 7; Fig. 9 a sectional elevation on the line 9—9 of Fig.

8 and Fig. 10 a plan view of one of the side rails.

Referring to the particular embodiment of 55 my invention as herein shown, the corner block is formed of two pieces of sheet metal bent to shape and assembled together and then secured together in suitable manner as by welding, preferably at several points as 60 hereinafter described. The two pieces of sheet metal are shown in Figs. 1 and 2 before they are bent to form at dotted lines indicating the lines of bending.

Referring first to the piece shown in Fig. 65 1 the same comprises a portion 1 which becomes a vertical plate which is curved to conform to the outer surface of the bed post which is here of the cylindrical type as shown in Figs. 3 and 4. This piece further 70 comprises a vertical side plate 2, a top plate 3 and a horizontal plate 4. When the piece is bent on the line 5 the two plates 1 and 2 become at right angles to each other. Likewise when the piece is bent on the line 6 the 75 top plate becomes at right angles to the side plate 2. So also when the piece is bent on the line 7 the plate 4 becomes at right angles to the side plate 2 and parallel to the top plate 3. The top plate is provided with an 80 extension 8 having a hole 9 for attachment of the end rail as hereinafter explained.

For attachment to the bed post the vertical plate 1 has holes 10 and 11 through which pass the bolts 12 and 13^a. For attachment of the side rails in a manner hereinafter explained the top plate 3 has a slot 12 to receive the squared or angular head of a fastening bolt and the plate 4 has a somewhat larger slot 13 to receive the lower end 90 of such bolt.

Referring to Fig. 2 the other piece comprises a vertical plate 14 adapted to fit against the plate 1, a vertical side plate 15, a top plate 16 and a bottom plate 17. By 95 bending on the line 18 the plates 14 and 15 become at right angles to form the vertical plate and side plate respectively. By bending on the line 19 the top plate 16 is formed at right angles to the side plate. By bending on the line 20 the bottom plate 17 becomes at right angles to the vertical side plate 15. The top plate is provided with an extension 21. By bending on the line 22 this 100

extension 21 becomes in line with and extends above the plate 14. This extension is provided with a hole 23 adapted to register with the hole 10.

- 5 The plate 14 is provided with a hole 24 adapted to register with the hole 11 of the plate 1. The top plate 16 is provided with a slot 25 adapted to register with the slot 12. The plate 17 is provided with a slot 10 26 adapted to register with the slot 13. The side plate 15 has a tongue 27 punched out therefrom and bent at right angles thereto along the line 28.

When the two pieces are bent in the manner above described the same are assembled together to form the corner block. In this assembly the plates 14 and 21 fit against the vertical plate 1 and are secured thereto preferably by spot welding. The top plate 20 16 is positioned below and against the top plate 3 and the bottom plate 17 fits on top of the bottom plate 4. The corner block structure may therefore be said to consist of a vertical plate or plates adapted to be secured to the bed post, two parallel plates at substantially right angles thereto such as the plates 2 and 15, these plates terminating at their outer ends in a casing rectangular in cross-section and composed of double 25 thicknesses of sheet metal at top and bottom by reason of the plates 3 and 16 at the top, and 4 and 17 at the bottom, and with single thickness of side wall consisting of the two parallel vertical plates 2 and 15 or rather 30 the other end portions of these plates. This casing is adapted to receive an end of a side rail in a manner hereinafter described. An end of an end rail is adapted to be received by the two right angled extensions 8 and 27 40 to which such end rail is secured by means of the bolts or rivets 29 and 30 passing through the holes 9 and 31 respectively as clearly shown in Figs. 3, 4 and 5.

The two pieces comprising the corner 45 block are preferably welded together not only along their vertical plates 1 and 14 as described but also along the meeting edges of the plates 15 and 3 as indicated at 32 in Figs. 3 and 7, and also along the free 50 edge of the bottom plate 4 where it meets the corner or bend between the side plate 15 and bottom plates 17, that is along the bending line 20. Such point of welding is at the point or line 33 as indicated in Fig. 7.

55 Describing the fastening means between a side rail and a corner block, the same consists of a peculiarly constructed bolt and sleeve thereon co-operating in the bolt holes in the corner block described. This bolt 34 60 has an angular head 35 at its upper end adapted to be received in the slots 12 and 25 and to slide laterally therein. The shank of this bolt is surrounded at a point within said casing by a sleeve 36 which together 65 with the lower end of the bolt extends

through the larger slots 13 and 26. A washer 37 is preferably provided at the upper end of the sleeve 36. A suitable nut such as the thumb nut 38 screws onto the lower end of the bolt, and against the lower end of the sleeve the bolt is preferably provided with a flange 39 to retain the nut thereon. The side rail 40 which is of the angle bar type, is provided with peculiarly shaped ends, each end being substantially arrow 75 shape with inclined outer ends 41 and opposite lateral recesses 42. The construction is such that when the end of the side rail is inserted into the casing of the corner block one of these inclined ends 41 will engage a side of the bolt or rather its sleeve 36 whereupon such bolt will be automatically shifted laterally to an end of the slot whereupon the rail is inserted to its full distance as shown in Fig. 8, after which the 80 bolt is slipped back laterally into normal position so as to be received within one of the recesses 42, whereupon the nut 38 is tightened and the corner block and rail thereby clamped firmly in position. The 85 side rails are thus detachable from the corner block but the end rails 43 are preferably permanently secured thereto by the rivets as already described.

I claim:

1. A corner block for bedsteads comprising a vertical plate adapted to be secured to the bedpost, two parallel plates at substantially right angles thereto, such plates terminating at their outer ends in a casing 100 rectangular in cross section, and adapted to receive a side rail, said plates having lower edges inclined upwardly and outwardly with inwardly turned portions forming the bottom of said casing, means in said 105 casing to secure such rail therein, and means on one of the two parallel plates to secure an end rail.

2. A corner block for bedsteads comprising a vertical plate adapted to be secured to the 110 bed post, two parallel plates at substantially right angles thereto, such plates extending latterly of the vertical plate and thence upwardly and terminating at their outer upper ends in a casing rectangular in cross section 115 and adapted to receive a side rail, said plates having lower edges inclined upwardly and outwardly with inwardly turned portions forming the bottom of said casing, means in said 120 casing to secure such rail therein, and means on one of the two parallel plates to secure an end rail.

3. A corner block for bedsteads comprising a vertical plate adapted to be secured to the bed post, two parallel plates at substantially 125 right angles thereto, such plates terminating at their outer ends in a casing rectangular in cross section and adapted to receive a side rail, said plates having lower edges inclined upwardly and outwardly with 130

inwardly turned portions forming the bottom of said casing, means in said casing to secure such rail therein, consisting of a laterally movable bolt adapted to automatically shift upon insertion of the side rail, in combination with a side rail having inclined ends and lateral recesses to receive such bolt.

4. A corner block for bedsteads comprising a vertical plate adapted to be secured to the bed post, two parallel plates at substantially right angles thereto, such plates terminating at their outer ends in a casing rectangular in cross section and adapted to receive a side rail, means in said casing to secure such rail therein, consisting of a laterally movable bolt adapted to automatically shift upon insertion of the side rail, two opposite sides of such casing having slots to accommodate the bolt in its shifting movements, in combination with a side rail having inclined ends and lateral recesses to receive such bolt.

5. A corner block for bedsteads comprising a vertical plate adapted to be secured to the bed post, two parallel plates at substantially right angles thereto, such plates terminating at their outer ends in a casing rectangular in cross section with double thickness of the metal of such plates at top and bottom of such casing, formed respectively by inturned upper and lower portions of said plates, means in said casing to secure such rail therein, and means on one of the two parallel plates to secure an end rail.

6. A corner block for bedsteads comprising a vertical plate adapted to be secured to the bed post, two parallel plates at substantially right angles thereto, such plates terminating at their outer ends in a casing rectangular in cross section with double thickness of the metal of such plates at top and bottom of such casing, said top and bottom having registering slotted openings, a bolt passing through such openings, in combination with a side rail having inclined ends and recesses coöoperating with said casing and its bolt.

7. A corner block for bedsteads comprising a vertical plate adapted to be secured to the bed post, two parallel plates at substantially right angles thereto, such plates terminating at their outer ends in a casing rectangular in cross section and adapted to receive a side rail, said plates having lower edges inclined upwardly and outwardly with inwardly turned portions forming the bottom of said casing, means in said casing to receive such rail therein, consisting of a bolt passing through the top and bottom of the casing and having a nut at one end, a sleeve on the bolt within the casing and between the head and nut of the bolt, in combination with a side rail having openings to receive the bolt.

8. A corner block for bedsteads comprising a vertical plate adapted to be secured to the bed post, two parallel plates at substantially right angles thereto, such plates terminating at their outer ends in a casing rectangular in cross section and adapted to receive a side rail, said plates having lower edges inclined upwardly and outwardly with inwardly turned portions forming the bottom of said casing, means in said casing to receive such rail therein, consisting of a laterally movable bolt passing through the top and bottom of the casing and having at one end an angular head received by said top and a nut at the other end, a sleeve on the body of the bolt within the casing, a washer between the sleeve and inner face of said top of the casing, in combination with a side rail having inclined ends and lateral recesses adapted to coöperate with the casing and bolt.

9. A corner block for beds made of two pieces of sheet metal formed into a block adapted to be attached to a bed post, one of said pieces comprising a vertical plate fashioned to fit the surface of the post, a side plate and a top plate, the other of said pieces comprising a vertical plate fitting against the other vertical plate, a side plate parallel to the other side plate, and a top plate fitting within the other top plate, the two side plates having at their outer ends two inturned plates fitting one upon the other, whereby a closed casing rectangular in cross section is formed at the outer ends of said plates with double plate thickness at top and bottom the lower edges of said side plates extending upwardly and outwardly and terminating in side walls for the casing.

10. A corner block for beds made of two pieces of sheet metal formed into a block adapted to be attached to a bed post, one of said pieces comprising a vertical plate fastened to fit the surface of the post, a side plate and a top plate, the other of said pieces comprising a vertical plate fitting against the other vertical plate, a side plate parallel to the other side plate, and a top plate fitting within the other top plate, the two side plates having at their outer ends two inturned plates fitting one upon the other, whereby a closed casing rectangular in cross section is formed at the outer ends of said plates with double plate thickness at top and bottom, said first named top plate and one of the side plates, each having a lateral extension to receive an end rail the lower edges of said side plates extending upwardly and outwardly and terminating in side walls for the casing.

11. A corner block for beds made of two pieces of sheet metal formed into a block adapted to be attached to a bed post, one of said pieces comprising a vertical plate fastened to fit the surface of the post, a side

plate and a top plate, the other of said pieces comprising a vertical plate fitting against the other vertical plate, a side plate parallel to the other side plate, and a top plate fitting within the other top plate, the two side plates having two inturned plates fitting one upon the other, whereby a casing rectangular in cross section is formed with double

plate thickness at top and bottom said second mentioned top plate having a vertical 10 extension in line with and above its vertical plate and fitting against the first named vertical plate said two inturned plates forming the bottom of the casing and said two top plates forming the top of such casing.

SAMUEL J. LAVEZZI.
